United States Patent Office.

LAWRENCE B. WATERMAN, OF CHICAGO, ILLINOIS, ASSIGNOR TO LOUIS B. KELLY, OF SAME PLACE.

Letters Patent No. 97,736, dated December 7, 1869.

IMPROVED CLOTHES-DRIER FOR STOVE-PIPES.

The Schedule referred to in these Letters Patent and making part of the same.

To all whom it may concern:

Be it known that I, LAWRENCE B. WATERMAN, of Chicago, in the State of Illinois, have invented certain new and useful Improvements in Clothes-Driers; and I do hereby declare that the following is a full, clear, and exact description thereof, reference being had to the accompanying drawings, making part of this specification, in which—

Figure 1 is a top view.

Figure 2, a partial vertical section.

My invention relates to that class of clothes-driers designed to be used upon stove-pipes, and consists in making a collar for the pipe, to be secured thereto by a thumb-screw, the collar having a flange at the bottom, on which a larger collar or ring rests, and being so fitted as to move readily around the inner collar, the outer collar being so constructed as to hold the clothes-bars, neither of the collars having any joint.

To enable others skilled in the art to make and use my invention, I proceed to describe its construction and operation.

A represents a metallic collar, which may be cast from any suitable metal, being in diameter adapted to the size of the stove-pipe with which it is to be used, and having a flange, *a*, at the bottom, and a thumb-screw, *c*.

B is a disk or ring of metal, having a vertical flange, *b*, fig. 2, which fits over the collar A, the flange *b* resting on the flange *a*, and fitting somewhat loosely, so that B may readily be turned around A.

Openings *f* are provided in B, to receive the arms *e*, upon which the clothes are to be hung.

Horn-like projections may be cast upon the outer edge of disk B, on which single articles can be hung.

The openings *g* are ornamental.

In use, the collar A is placed upon the pipe, passing over the same, and is secured thereto in any desired position by means of the thumb-screw *c*. Disk B is then placed over the collar A, *b* resting on *a*. The arms *e* are then inserted in the openings *f*.

The several parts are whole, having no joints, and requiring no devices to secure the parts together.

The whole device can be raised or lowered upon the pipe by the use of the thumb-screw.

The disk B can be easily revolved around the collar A, and thus the several arms *e* can be brought, from time to time, over the stove where there is the most heat.

When all the arms are removed, a number of articles can still be hung upon the points *d*.

In fig. 2 of the drawings, the disk B is only shown on one side of the collar A.

What I claim as my improvement, is—

The arrangement of the collar A with its flange *a* and thumb-screw *c*, in combination with the disk or ring B, with its projections *d* and slots *f*, as shown and described.

Witnesses: LAWRENCE B. WATERMAN.
